UNITED STATES PATENT OFFICE.

FREDERICK PRICE, OF SCRANTON, PENNSYLVANIA.

TOWEL RING.

Application filed September 24, 1923. Serial No. 664,527.

To all whom it may concern:

Be it known that I, FREDERICK PRICE, a citizen of the United States, residing at Scranton, in the county of Lackawanna and 5 State of Pennsylvania, have invented a new and useful Towel Ring, of which the following is a specification.

This invention has reference to napkin or towel hangers, the primary object of the 10 invention is to provide a device of this character which may be readily and easily positioned over a supporting nail or hook, the structure being such as to relieve the napkin or towel of unnecessary strain usually directed thereto when the napkin or towel is positioned over a hook, while the same is 15 in use.

Another important object of the invention 20 is to provide a device of this character which may be readily and easily connected to a towel, due consideration being given to the gripping qualities of the hanger.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:

35 Figure 1 is a front elevational view of a holder and support constructed in accordance with the invention.

Figure 2 is a rear elevational view thereof.

40 Figure 3 is a side elevational view disclosing the relation of the gripping fingers of the ring.

Figure 4 is a bottom view thereof.

Figure 5 is an elevational view disclosing

a portion of a towel as supported thereby. 45

Referring to the drawing in detail, the device includes a body portion indicated generally by the reference character 5 which is constructed of suitable flexible material such as celluloid, hard rubber or the like. 50

This body portion is preferably circular in formation as clearly shown by Figures 1 and 3 of the drawing and is formed with right angled end portions 6 and 7 respectively, the end portion 6 extending laterally, 55 while the end portion 7 extends rearwardly providing interlocking fingers adapted to grip an article therebetween, in a manner as shown by Figure 5 of the drawing.

Formed on the extremities of the fingers 6 and 7 are heads 8 that provide guards that cooperate with the adjacent surfaces of the fingers to hold and grip an article positioned between the fingers. 60

From the foregoing it will be obvious that 65 an article such as a napkin or towel may be readily positioned between the gripping fingers of the holder and the ring portion thereof placed over a suitable hook or nail to support the towel. 70

What is claimed is:—

In a holder of the class described, a curved resilient body portion, one end of the body portion extending at right angles and provided with a head, said head adapted to 75 cooperate with the body portion to provide a keeper for the opposite end of the body portion, and the opposite end of said body portion extending laterally and provided with a head. 80

In testimony that I claim the foregoing as my own, I have hereto affixed my signature in the presence of two witnesses.

FREDERICK PRICE.

Witnesses:

RAY JENKINS,

WILLIAM WHITTINGTON.
